UNITED STATES PATENT OFFICE.

DAVID EDWARD WELSH, OF LOS ANGELES, CALIFORNIA.

AMUSEMENT DEVICE.

Application filed January 24, 1921. Serial No. 439,684.

To all whom it may concern:

Be it known that I, DAVID EDWARD WELSH, a citizen of the United States, residing at the city of Los Angeles, county of Los Angeles, and State of California, have invented 5 certain new and useful Improvements in Amusement Devices, of which the following is a clear and exact description, enabling those skilled in the art to which it appertains to make and use the same.

This invention relates to amusement devices, and more particularly to an amusement device having the form of a rotatable playing table superimposed upon a rotatable 15 platform and adapted to oscillate relative to said rotatable platform in the manner substantially as described.

An object of this invention is to produce 20 an amusement device which is harmless in character, simple in construction and yet interesting and exciting to the players as well as to the spectators.

It is a still further object of this invention 25 to provide a rotatable platform, and superimposed thereon, and universally connected therewith, a playing table and suitable mechanical means on the rotatable platform to enable the operator of this device to impart an oscillating motion to the superimposed 30 playing table, while both table and platform may be stationary or rotated by independent mechanical means in the manner substantially as shown.

Heretofore in amusement devices of this 35 character the amusement feature has depended solely upon the action of centrifugal forces, thus:

The persons playing are first grouped seated in the center of the table. The device 40 is then set in rotative action and the speed gradually increased until the players so grouped are displaced by centrifugal action and scattered in all directions from the center outward toward the periphery of the 45 table.

This scattering action comprises all the amusement produced and the play thus terminates, the operator having no power to further control the movements of the 50 players.

In the operation of my device herein described, the most conspicuous feature of novelty lies in the capability of the operator to control the movements of the players at 55 will.

It is an object of my invention to produce

a machine in which the players may be grouped at different points, and regrouped on different portions of the table during play at the will of the operator, a typical 60 method of operation being outlined as follows: The players are seated around the periphery of the playing table, the rotatable platform and playing table are together set in slow rotation; the mechanism governing 65 the inclination or reciprocation of the playing table may be then set in motion and the playing table gradually inclined until the players on the raised side are displaced and slide diametrically across the table.

Automatic reversal of the tilting action 70 reverses the sliding direction of the players and also displaces the players who are on the low side and were not displaced by the first tilt.

All the players are now sliding back and forth across the slowly revolving table.

The operator may now change the first 75 plane of inclination to a second plane of oscillation at 90° from the first (by switching the power from one mechanism to another) causing the players to change their direction of movement, and to slide back and forth across the table on a plane of inclination at right angles to their first line of 80 movement.

Sense of direction is annulled by the revolving table; the direction of the planes of inclination cannot be defined by the players, and apparently occur at any or all points of 85 the circle.

The change from the line of movement of the players sliding back and forth to another line of movement at right angles to the first causes great confusion, the operator 90 having the capability of continuing or alternating the different lines of movement at will.

This confusion of the players sliding about the surface of the table (apparently 100 in all directions) with involuntary and constantly changing groupings constitute the main amusement factor of this device.

When it is desired to terminate the play, the operator brings the table to the horizontal 105 position, then gradually increases the speed until centrifugal force becomes active and spins the players from their grouped positions on the table to substantially their original positions around the periphery. 110 The table is then brought to rest.

This one final action, viz, the spinning of

the players from the center or other positions on the table outwardly to the periphery of the playing table constitutes the entire amusement efficiency of all existing centrifugal action amusement devices.

In the figures, 1 is a suitable foundation, made preferably of a cement. 2 is a metal base mounted upon said cement base 1, and having an aperture in its center to accommodate a vertical shaft 4, to which is attached a collar 3. 5 is a soft metal ring, made preferably of a bearing metal such as a bronze, and adapted to take a portion of a possible load, which may be imposed upon it by a slight deflection of the center part of the reciprocal platform 6. 7-7 are a plurality of wheels, mounted upon bearings such as the short shafts 8, said wheels being rigidly attached to the platform 6 and running upon a circular endless track 9. 10 represents a driving pulley, mounted on a driving shaft 11. 12 is a flexible cable passing over the drive pulley 10 and around the groove 13, which extends completely around the periphery of the turntable 6. 15 is the side wall of a suitable inclosure. 16 is the plane table, upon which the players are placed in the manner hereinbefore set forth for the purpose of playing. The table 16 is mounted upon a universal coupling or what may be termed gimbals designated as 17, at the top of the vertical shaft 4; thus the degree of inclination of the table 16 is controlled entirely by a plurality of cables, two of which are represented in Figure 2 of the drawings by 18 and 19 respectively, these cables being representative only of suitable means to cause the inclination or oscillation of the table 16. 20 and 21 are a plurality of idling pulleys, commonly termed sheaves. 22 represents two endless chains running over sprockets 30 and 31, the same being coupled together by a connecting link 23, to which is attached the cables 18 and 19 respectively. 24 is a small pulley adapted to drive the chains 22 over the sprockets 30 and 31, by means of a flexible chain extending from sprocket 24 to sprocket 25, which may be driven by a motor 26 best suited to this purpose. It will thus be seen that a continuous rotary motion, caused by the motor 26, imparted by sprocket 25 to sprocket 24, will cause the endless chains 22 to continuously travel over the sprockets 30 and 31. This continuous motion will cause the coupling 23 to travel from one set of sprockets 30 to the other set of sprockets 31, and then return to 30, causing a reciprocating motion. This recip-

rocating motion is imparted to cables 18 60 and 19 respectively, which convey the same by means of the couplings 27 and 28, to a substantial part 29 of the playing table 16; thus a continuous oscillation of the table 16 may be produced from the motor means 65 mounted on table 16, entirely independent of the outside driving means 10 and 11, adapted to cause the rotation of the entire unit in the manner and for the purpose as hereinbefore fully set forth. 70

I claim:

1. An amusement device comprising a primary turntable, means to rotate same, a vertical shaft through the center, a secondary superimposed playing table mounted 75 upon a gimbal at the top of the vertical center shaft, means on the primary turntable, under control of the operator, adapted to cause the oscillation of the secondary playing table on either one of two axes, 80 said axes being at an angle of 90° to each other.

2. In amusement device the combination with a primary circular turntable free to rotate, of a center shaft therethrough, a 85 superimposed playing table universally mounted on top of said center shaft, of means on said turntable to produce a continuous oscillation of the superimposed playing table on either one of two axes, the 90 one axes of oscillation 90° from the other, said oscillation to be independent of any rotation.

3. A circular turntable, a circular track thereunder, a plurality of wheels attached 95 to said turntable and adapted to run on said track, a vertical center shaft, a universal coupling at the top of said center shaft, a superimposed playing table mounted on said center shaft and means on the 100 turntable to cause a continuous or intermittent oscillation of said superimposed playing table on either one of two axes, said axes being at right angles the one to the other. 105

4. In an amusement device a circular primary table free to rotate, a secondary superimposed table mounted centrally of said primary table by means of a universal coupling, a plurality of cables attached to said superimposed table in proximity to its periphery, said cables operating over sheaves suitably placed on said primary table and a source of power suitably connected with said cables in a manner to cause the operation and oscillation of said superimposed table on either one of two axes. 115

DAVID EDWARD WELSH.
